OSCILLATOR MODULATOR

Edward J. Coxey, Little Falls, N. J., assignor to
 Federal Telephone and Radio Corporation, New
 York, N. Y., a corporation of Delaware

Application April 4, 1944, Serial No. 529,449

8 Claims. (Cl. 179—171.5)

1

This invention relates to new and useful improvements in electric oscillators and more particularly in oscillator-modulator circuits producing oscillations and applying such oscillations to modulate a high voltage supply such as is used in radio transmitters.

One of the objects of this invention is to provide a modulator-oscillator with a minimum of parts.

Another object of the invention is to reduce circuit losses to a minimum and to obtain 100% modulation by simple means.

A further object of the invention is to provide a fully modulated D. C. power supply for an intermediate or the final stage, particularly for the tank circuit of a transmitter as used in ship communications or wherever a modulator using a minimum of components is needed.

A specific object of the invention is to provide a single inductance element, serving both as oscillator and modulator element.

Still another object of the invention is an audio-oscillator modulating a transmitter by means of a combined oscillator and modulator transformer.

An additional object of the invention is an audio-oscillator, of the magnetic or capacitive feedback type, comprising a transformer serving simultaneously as an oscillation inductance and as a modulation transformer feeding the plate circuit of an intermediate or the final stage of a radio transmitter.

Further objects and advantages of the invention will be apparent from the following description applied to the drawing.

A preferred embodiment of the invention is diagrammatically shown in the drawing, Fig. 1 illustrating as much of an audio frequency oscillator of the Hartley type as is necessary for an understanding of the principles of the invention. Fig. 2 is a diagram of a modified circuit.

In Fig. 1, 1 is an audio-oscillator tube in circuit with a transformer 2. Winding 3 of transformer 2 connects, at one terminal, to the grid of tube 1 and, at its second terminal, over grid leak resistor 4 and grid blocking condenser 5 to ground. Second winding 6 of transformer 2 connects to the plate of tube 1. The oscillator thus formed represents a modified Hartley or magnetic feedback circuit. Tuning condenser 12 may be used in parallel with transformer winding 6 or with any other part of transformer 2, as required. Transformer winding 6 is connected to the high voltage B+ and also grounded over by-pass condenser 7. B+ supplies plate

current and feeds a tank circuit 11 in a preliminary or the final stage of a radio frequency amplifier. The modulated voltage is taken off at 8 from the oscillator-modulator circuit. 9 is a radio frequency by-pass condenser.

In this diagram the single component 2 is shown to operate as a modulation transformer as well as an inductance of the oscillator circuit.

Instead of a transformer such as shown in Fig. 1, an autotransformer or any other inductive coupling means may be used as required to achieve the object of the invention.

The circuit shown in Fig. 2 employs a modified Hartley oscillator, the inductive portion of which, 15 an auto-transformer 13, is extended at 14 to match the load impedance presented by the modulated radio frequency amplifier 15. This may be used to obtain a 100% modulation supply of D. C. for a preliminary or the final stage of a radio transmitter.

The invention is not restricted to modulating the D. C. supply of a final amplifier stage. It may be found desirable to plate modulate a low power stage and amplify the modulated output 25 of the low power stage by means of higher power linear amplifiers.

The invention is not limited to the type of oscillator shown. Many types of oscillators, such as capacity feedback oscillation circuits may be 30 adapted to obtain oscillation-modulation in accordance with the invention, without exceeding the scope thereof.

The invention is not limited to the method and type of modulation in which the modulating signal is applied in the plate circuit of a radio frequency power amplifier.

There is no limitation to the frequency or frequency range which may be used in accordance with this invention as modulator frequency or carrier frequency. However, the invention may offer particular advantages for the modulation of a high voltage D. C. power supply used in marine transmitters.

What is claimed is:

45 1. An oscillator-modulator system for a radio transmitter having a plurality of stages, comprising an oscillator tube for producing audio frequencies, said tube having a grid circuit comprising one winding of a transformer, a tank circuit comprising a second winding of said transformer, a source of positive D. C. power supply applied to one end of said second winding, capacitance tuning means in parallel to said second winding, a tank circuit of a high frequency 50 amplifier, the other end of said second winding

containing an inductance portion extending beyond the first mentioned tank circuit and connected to said tank circuit of a high frequency amplifier and a high frequency by-pass capacitance connecting to said inductance portion.

2. In a radio transmitter, a high frequency amplifier, a high voltage direct current source, a coil with high inductive reactance connected between said source and said amplifier, the impedance of said coil approximately matching, at an audio frequency, the load impedance presented by the output circuit of said high frequency amplifier, means for adjusting the impedance of the coil and an audio oscillator coupled across a portion of said coil to modulate to cut off the direct current flowing through the coil to said high frequency stage.

3. In a radio transmitter, a high frequency stage, a high voltage direct current source, a single winding coil with substantial inductive reactance connecting said source to said stage, the impedance of said coil approximately matching, at an audio frequency, the output impedance of said high frequency stage, a tuning capacitor and means including a space discharge device connected across spaced points on said coil for generating and superposing a pulsating voltage at the said audio frequency on the direct current flowing to said high frequency stage, the magnitude of said current being sufficient at alternate peak values to substantially stop the flow of current from said source to said transmitter.

4. In a device for modulating the output of a carrier frequency system, a source of anode current for said system, an inductive winding having a plurality of connections thereto, one of said connections being adjustable, a space discharge device connected as an oscillator utilizing a portion of said winding as an inductive element, and other connections from said source to said system including a part of said portion of said winding utilized as an inductive element and another portion extending beyond said first-named portion and including said adjustable connection.

5. In a device for modulating the output of a carrier frequency system, a source of anode current for said system, an inductive winding having a plurality of connections thereto, one of said connections being adjustable, a space discharge device connected as an oscillator modulating said output and utilizing a portion of said winding as an inductive element, and other connections from said source to said system including a part of said portion of said winding utilized as an inductive element and another portion extending beyond said first-named portion and including said adjustable connection, said adjustable connection being further connected to determine in part by its position the degree of modulation produced in said system by said oscillator.

6. In a device for modulating the output of a system containing one or more space discharge devices, at least one of said devices operating as

an oscillator, a source of anode voltage, a connection leading to the anode circuit of one or more space discharge devices within said system, an inductive winding having an adjustable portion thereof joining said source and said connection, a space discharge device external to said system having a cathode, an anode and a control grid, a second connection from said cathode to ground, a third connection through a blocking condenser from said control grid to the end of said winding not included in said first-named portion, a fourth connection from said anode to a point in said first-named portion of said winding, and a variable capacitor connected across said winding end and said point, whereby said external space discharge device will operate as an oscillator producing a degree of modulation of said system determined in part by the particular setting of said adjustable winding portion, said variable capacitor serving in part to determine the frequency of said oscillations.

7. In a device for modulating the output of a system containing an oscillator, a source of anode voltage, a connection to the anode circuit of said system, a winding connected in said anode circuit a plurality of taps on said winding, a space discharge device having a cathode, an anode and a control grid, a connection from said cathode to ground, a second connection from said control grid through a blocking condenser to one end of said winding, a third connection from the one of said taps nearest said oscillator anode connection to said anode, a variable capacitor connected across said last-named tap and said end of said winding, a fourth connection from said source to a second tap intermediate said winding end and said first-named tap, and a fifth connection from said system anode circuit connection to said winding, said connection being adjustably connectable to those portions of said winding at, in proximity to, and extending beyond said first-named tap.

8. In combination: an amplifier and means for modulating said amplifier comprising an oscillator and a transformer, a portion of said transformer coupled to said oscillator and forming the tank circuit thereof, a direct voltage supply source coupled to said one portion, and means for coupling said amplifier to another portion of said transformer for modulation thereby.
